ADJUSTABLE TYPE CASE

Ralph I. Scheuer, Two Rivers, Wis., assignor to
Hamilton Manufacturing Company, Two
Rivers, Wis., a corporation of Wisconsin

Application March 2, 1936, Serial No. 66,574

12 Claims.

(Cl. 276—44)

This invention relates to adjustable type cases more particularly for storage in printing plants of printing material such as leads or slugs arranged in groups of equal widths.

5 Among other objects, the invention aims to provide an adjustable case which can be adjusted to take the place of any one of many cases which have been heretofore required to accommodate varying sizes of printing material.

10 While adjustable cases broadly are not new, this invention provides a greater range of adjustment and substitution than has been heretofore possible in adjustable cases, and at the same time, the finer adjustment provided enhances the operative effectiveness of the device by making it extremely unlikely for the printer when filling the case or when putting used printing material back into the case, to get the material into the wrong group division. This is accomplished, in 15 accordance with the invention, by reducing the required play between the printing material and the division members between the groups of material, to a minimum.

Other objects and advantages will be apparent 20 from the following description, and the invention may be readily understood by reference to the accompanying drawing, in which—

Figure 1 is a plan view showing generally a device embodying the invention;

Figure 2 is an enlarged portion of the structure 25 of Fig. 1;

Figure 2a is a very much enlarged partial view 30 of the slots and division members as arranged for one size of slug;

Figure 2b is a view similar to Fig. 2a but for another size of slug;

Figure 3 is a cross section on the line 3—3 35 of Fig. 2; and

Figure 4 is a perspective view of one of the 40 division members.

Referring in detail to the illustrative structure shown in the drawing, the numeral 10 indicates generally a type case embodying my invention and which is shown in the form of a wide relatively shallow drawer-like container, having the flat bottom 11, front and rear walls 12 and 13 respectively and side walls 14 and 15 respectively, all of which may be advantageously constructed of one piece of sheet metal. In this instance partition members 16, spaced apart from front to rear of the container, run width-wise thereof between the side walls 14 and 15. These partitions 16 are here shown formed of wood or the like but might of course also be of metal. In 45 accordance with the invention also the front wall

12 and the rear wall 13 are also provided with members 16 which while not strictly partition members are similar in structure and function to the intermediate members 16. As best shown in Fig. 3 the members 16 may be permanently secured in the container as by screws 17 passing through the bottom 11 into the lower edges of the members 16 with the heads of the screws countersunk to be flush with the bottom 11.

The members 16 are uniformly grooved or 5 slotted at small intervals throughout their lengths by vertically extending slots 18 formed therein, the intermediate members 16 having these slots upon both their forwardly and rearwardly directed faces while the members 16 associated with the front wall 12 and rear wall 13 have these slots only upon their rearwardly and forwardly directed faces respectively.

In accordance with the present invention the slots 18 are extremely narrow and are desirably 20 no more than approximately $\frac{1}{32}$ of an inch wide, and are spaced apart between centers a distance or length substantially $1\frac{1}{2}$ of an inch, or a length of one em or pica. It will thus be noted for purposes presently to be pointed out that one-half of a slot width equals $\frac{1}{64}$ of an inch. As is 25 well known in the art, a pica is a unit of length used in measuring the width of type, and is itself equal to twelve points, so-called, or $1\frac{1}{72}$ of an inch, a pica sometimes also being referred to as 30 an em.

For association with the slots 18, the invention provides division members 19 for dividing the spaces between pairs of partition members 16 into spaces of varying width each for receiving a group of type slugs 20, 21, 22 or 23, etc. These type slugs may be lines of type integrally formed together as by Linotype machines, or they may be leads for spacing lines of type apart. In any event, a group of these leads or slugs of equal length are intended to be stored between a pair of the division members 19, these division members being adjustably interchangeable to provide spaces for the various groups, so that a slug of a given length may be readily located when desired. The division members 19 are desirably formed as best shown in Fig. 4 out of a single piece of sheet metal of a thickness slightly less than $\frac{1}{32}$ of an inch, (so as to fit the slots 18) folded upon itself with the folds spaced apart 45 so as to provide an over-all thickness of the member, that is, a distance between the outer faces of the folds, of $\frac{7}{72}$ of an inch, or nine points. Extending laterally beyond the folds integrally with one of the folds 24 and in the plane 50

thereof, are the tongues 25 which are thus adapted to be received in registering opposite slots 18. Thus also the other fold 26 of the member 19 is offset from the plane of the tongues 25. It will be understood, as best shown in Fig. 2, that the division members 19 may be inserted in the slots in either way, that is with the offset fold 26 of the division member facing either to the right or to the left as desired, for the purpose next described.

For example, as best shown in Fig. 2, to form the space 27 between two of the division members 19, these division members for the space 27 are inserted in pairs of slots 6 picas or $7\frac{1}{2}$ of an inch apart ($6 \times 1\frac{1}{2}$). However, the division members 19 are disposed with their offset folds 26 facing in the same direction, which thus causes the over-all thickness of one of the division members to reduce the size of the space 27 by 9 points ($\frac{1}{2}$), leaving a net distance for the space 27 of 63 points ($6\frac{1}{2}$). Thus the 5 pica slugs 20, which have a length of $6\frac{1}{2}$ of an inch, are just received in the space 27 with a play of 3 points or $\frac{3}{2}$ of an inch. Thus also a $5\frac{1}{2}$ pica slug, which has a length of 66 points ($5\frac{1}{2} \times 1\frac{1}{2}$) would not fit in the space 27; and a $4\frac{1}{2}$ pica slug, which would be only 54 points in length, would allow 9 points play, which would be so much play that the printer would readily note that it was in the wrong place.

For accommodating a $5\frac{1}{2}$ pica slug or lead 21 the space 28 may be provided utilizing the division member 19 to the left of the space 27 as the division member at the right of the space 28 and disposing another division member 19 6 picas (6 slots 18) further to the left, but with its folded-over portion 26 facing in the opposite direction. Thus the space 28 is a 6 pica distance unreduced by the folded-over portions of any division member. While the space 28 is not reduced by the folded-over portion of either of the division members 19 at the sides of this space, the distance between the division members (and even though they are in slots 6 picas apart) is slightly less than 6 picas. The reason for this will be evident by reference to Fig. 2a in which the size of the slot is exaggerated for clearness of description. When the division members face in opposite directions, and are in the slots having their centers 6 picas apart, since the width of each slot is $\frac{1}{2}$ of an inch, the division members will reduce the distance between the centers of slots by twice one-half the width of each slot or $\frac{1}{2}$ of an inch ($2 \times \frac{1}{4}$). In other words, $\frac{1}{2}$ of an inch must be deducted from the distance between the centers of the slots ($7\frac{1}{2}$) to arrive at the actual distance between the faces of the division members 19 forming the space 28 which gives us $7\frac{1}{2}$ of an inch minus $\frac{1}{2}$ of an inch. Since a $5\frac{1}{2}$ pica slug is 66 points long ($5\frac{1}{2} \times 1\frac{1}{2}$) the play in the space 28 is 6 points minus $\frac{1}{2}$ of an inch ($7\frac{1}{2}$ minus $6\frac{1}{2}$ minus $\frac{1}{2}$). The play of 6 points minus $\frac{1}{2}$ of an inch ($\frac{1}{2}$ minus $\frac{1}{2}$) is a trifle over 3 points or what I have called 3 plus. It is in fact $3\frac{1}{4}$ points; but since for present purposes the extra $\frac{1}{4}$ point play is practically infinitesimal the play in space 28 with a $5\frac{1}{2}$ pica slug 21 may be considered to be substantially 3 points. Since the next size slug or 6 pica is $7\frac{1}{2}$ of an inch long, it could not be placed in the space 28, and the next smaller size or 5 pica would be received in the space 28 with a play of more than nine points, which would be too much play.

75. Similarly, another space 29 may be provided

for the 6 pica ($6 \times 1\frac{1}{2}$) slugs 22 by utilizing the division member 19 at the left of the space 28 and disposing another division member 19 to the left thereof in the pair of slots 7 picas away but with the two division members forming the space 29 having their folded-over portions 26 facing in the same direction. When, as in spaces 27 and 29, the division members face in the same direction, the width of the slot may be disregarded in figuring the distance between the division members, since the amount added to this distance at one side of the space ($\frac{1}{2} \times \frac{1}{2}$) must be deducted at the other side of the space. The space 29 therefore accommodates the slugs 22 with a play of exactly 3 points ($7 \times 1\frac{1}{2}$ equals $8\frac{1}{2}$), 15 minus $\frac{1}{2}$ equals $7\frac{1}{2}$, minus $\frac{1}{2}$ leaves $\frac{3}{2}$). Since a $6\frac{1}{2}$ pica slug is $7\frac{1}{2}$ of an inch long, it could not be put in the space 29 which affords a slug length of only $7\frac{1}{2}$ of an inch, and the next smaller size or $5\frac{1}{2}$ pica would be received in the space 29 with a play of more than nine points, which would be too much play.

For the $6\frac{1}{2}$ pica slug the space 30 is provided by using the division member 19 to the left of the space 29 and placing another division member 19 still further to the left as shown in Fig. 1. In this instance the division members for the space 30 have their folded-over portions 26 facing in opposite directions but with these offset folded-over portions toward each other, that is, 30 facing inwardly into the space 30 in contrast with the space 28 where the division members were facing in opposite directions with their offset folded-over portions facing away from the space 28. The division members for the space 30 35 are disposed in slots 8 picas apart which is a distance from center to center of the slots of $9\frac{1}{2}$ of an inch. As will be seen from Fig. 2b, if the outer faces of the division members were exactly on the center line of the slots, it would be 40 necessary to deduct from $9\frac{1}{2}$ of an inch twice the over-all thickness of the division members ($2 \times \frac{1}{2}$) which would leave $7\frac{1}{2}$ of an inch. It will be noted however that a $6\frac{1}{2}$ pica slug is $7\frac{1}{2}$ of an inch long itself, and consequently if 45 there were no play the slug 23 could not be received in the space 30. By further reference to Fig. 2b, however, it will be seen that the outer faces of the division members are one-half the width of the slots outside of the center line of 50 the slots so that there must be added to the distance of $7\frac{1}{2}$ of an inch for the space 30 twice the width of one-half of each slot on each side of this space 30 or $\frac{1}{2}$ of an inch ($2 \times \frac{1}{4}$). Thus the actual net width for the space 30 is $7\frac{1}{2}$ of an 55 inch plus $\frac{1}{2}$ of an inch; this allows a play for a $6\frac{1}{2}$ pica slug of $\frac{1}{2}$ of an inch. Reducing this to terms of points we find that it equals $2\frac{1}{4}$ points or what I have called 3 minus. Since for present purposes the difference between $2\frac{1}{4}$ points and 3 60 points, or $\frac{1}{4}$ of a point, is practically infinitesimal, the play in the space 30 with a $6\frac{1}{2}$ pica slug 23 therein may be considered to be substantially 3 points. Since the next size slug or 7 pica is $8\frac{1}{2}$ of an inch long, it could not be placed in the space 30 the total available width of which is $80\frac{1}{4}$ 65 points. The next smallest size slug or 6 pica which is $7\frac{1}{2}$ long would be received in the space 30 with a play of $8\frac{1}{4}$ points which would be too much play.

Label holders 101 may be carried by the member 16 along their top edges, as clearly shown in the drawing, without interfering with the function of the slots 18, these label holders carrying labels such as the labels 102 indicating the slug 75

sizes of the compartments provided as described. Thus in each case a play of substantially 3 points, with in no case much more or less than this, can be provided for. This very small maximum of play has a number of novel results: As pointed out, it guards against a slug of a larger size being accidentally placed in a space provided for a smaller size slug. Furthermore, the printer soon gets accustomed to appreciating either by sight or by feel, the substantially 3 points play normally provided for, and is wholly unlikely to place a slug in a space larger than the one provided for that size of slug. Thus accuracy of storing is assured with a minimum of effort on the part of the printer in placing the slugs in the spaces. Moreover, the small maximum play, provided, effects great flexibility in the sizes and number of spaces which may be obtained in any one container, thus making for standardization of manufacture and reduction of cost both in inventories and equipment.

Manifestly, the invention is not limited to details of construction shown for purposes of exemplification, and such changes may be made as fall within the scope of the claims.

Having described my invention, I claim:

1. As an article of manufacture, a division member for an adjustable type case of the class described, embodying a folded metal sheet, and tongues at the ends thereof, the metal being folded to provide an over-all thickness for the member of nine points.

2. As an article of manufacture, a division member for an adjustable type case of the class described, embodying a folded metal sheet, and tongues at the ends thereof, the metal being folded to provide an over-all thickness for the member of nine points, in combination with a container provided with means for adjusting the division members by widths apart varying by one pica.

3. In an adjustable type class, the combination of a shallow drawer, partitions running width-wise of the drawer, pairs of oppositely registering slots in said partitions, adjacent pairs of slots being spaced apart a width of twelve seventy-seconds of an inch between slot centers, and division members removably receivable in the slots of a pair.

4. In an adjustable type case, the combination of a shallow drawer, partitions running width-wise of the drawer, pairs of oppositely registered slots in the partitions, adjacent pairs of slots being spaced apart a length of twelve seventy-seconds of an inch between slot centers and the slots being approximately one thirty-second of an inch wide, metal division members having tongues received in the slots of a pair, said division members being approximately nine seventy-seconds of an inch thick, and said tongues being at one side of said thickness whereby the division members are reversible to vary the distance between division members received in adjacent pairs of slots with or without changing the pairs of slots in which the division members are received.

5. As an article of manufacture, a division member for an adjustable type case of the class described embodying a folded metal sheet of material not more than approximately one thirty-second of an inch thick, said material being folded upon itself with the folds spaced apart to provide an over-all effective thickness for the folded sheet of approximately nine seventy-seconds of an inch, portions of the sheet integral with one of the folds and in the plane thereof extending laterally

beyond the folds of each side thereof to form tongues.

6. As an article of manufacture, a drawer for an adjustable type case of the class described having partitions running width-wise of the drawer, pairs of oppositely registering slots in said portions, said slots being approximately one thirty-second of an inch wide and spaced apart approximately twelve seventy-seconds of an inch between slot centers. 10

7. In an adjustable type case, the combination of a support, parallel partition members on said support, slots in said partition members arranged not more than one pica apart, and movable division members receivable in said slots whereby 15 the spacing between the division members is adjustable by widths varying by not more than one pica.

8. In an adjustable type case, the combination of a support, parallel partition members on said support, slots in said partition members arranged not more than one pica apart, and movable division members having portions receivable in said slots, said division members having portions not receivable in said slots of greater thickness than the portions receivable therein and the latter being offset from the center of the over-all thickness of said division members, whereby the division members are adjustable apart distances varying by not more than approximately 25 one-half pica.

9. In an adjustable type case, the combination of a support, parallel partitions mounted on said support, pairs of oppositely registering slots in said partitions, said slots being a fraction of a 35 pica in width and the pair of slots being spaced apart a distance of not more than one pica, and movable division members received in said slots.

10. In an adjustable type case, the combination of a support, parallel partitions mounted on 40 said support, pairs of oppositely registering slots in said partitions, said slots being a fraction of a pica in width and the pair of slots being spaced apart a distance of not more than one pica, and movable division members received in said slots, 45 said division members having an over-all thickness greater than the width of said slots.

11. In an adjustable type case, the combination of a support, parallel partitions mounted on said support, pairs of oppositely registering slots 50 in said partitions, said slots being a fraction of a pica in width and the pair of slots being spaced apart a distance of not more than one pica, and movable division members received in said slots, 55 said division members having an over-all thickness greater than the width of said slots, the portion of the division members receivable in the slots being offset from the center of the over-all thickness of said division members.

12. In an adjustable type case of the class described, the combination with a pair of regularly slotted fixed partition members with their slots facing each other and transversely aligned, of a pair of separable division members each having aligned tongues at their respective ends receivable 65 in a pair of said aligned slots and each division member having a portion to one side thereof offset from said tongues whereby said division members may be associated with said partition members with the division members having their 70 offset portions facing in the same direction or in opposite directions selectively.
